BLOCK SIGNAL SYSTEM

Chauncey G. Suits, Madison, Wis., assignor to
General Electric Company, a corporation of
New York

Application December 5, 1929, Serial No. 411,929

28 Claims. (Cl. 246—34)

My invention relates to railway block signal systems, and it has for one of its objects to provide a signal system which operates entirely electrically.

- 5 A further object of the invention is to provide certain improvements in systems of the type indicated whereby the signals of such a system may be more satisfactorily and reliably controlled than has been possible heretofore.
- 10 A further object of the invention is to provide means whereby the signals of an occupied block and also those of the adjacent blocks may be controlled in accordance with the condition of the different blocks through means entirely electrical.
- 15 Thus, for example, in the usual form of signal system, means are provided whereby the signal or signals at the entrance of a block which is occupied by a vehicle are caused to indicate "danger" and, the signal or signals at the entrance to the block at the rear of the vehicle are caused to indicate "caution" the latter indication being frequently dependent upon the presence of a following vehicle in the second block to the rear. It is also well known signal practice to have all of the signals normally deenergized and to provide means whereby when a vehicle enters any block the signals of the block in advance indicate "safe" or "clear" dependently upon the condition of the advance block.
- 20 Thus one of the objects of my invention is to provide means entirely electrical whereby the signals may be controlled in accordance with well-known practices and in which both the "caution" and "safe" signals may be operated in response to the movements of a vehicle and dependently upon the position of other vehicles upon the track.

In carrying my invention into effect I provide an electron discharge device in each block which is controlled in accordance with track conditions, that is, in dependence upon the occupancy of the respective block by a vehicle. The anode current of each of these discharge devices is then employed to control a number of reactors located in the blocks at which signals are to be controlled. These reactors are of the iron core type and have a winding of which the impedance varies over a wide range dependently upon the degree of saturation of the core. These windings are employed to control the energization of the different signals in response to operation of the discharge devices and hence in accordance with track conditions.

By means of the type indicated the signals may be controlled as is desired in accordance with

well known signal practice and by means employing a minimum of discharge devices and, as will later appear, a minimum of line conductors extending between adjacent blocks.

Thus a further object of the invention is to provide means entirely electrical whereby the desired signal operation may be carried out and which employs a minimum of discharge devices.

By the expression "entirely electrical" as used in this application I have reference to a system in which all of the component parts are maintained in fixed mechanical relation and the operative effect of which is due entirely to electrical conditions within the structure. Such a system may be considered, for example, in contrast to a system the operative effect of which is due to a mechanical movement, such as that of the armature of an electro-mechanical relay.

A still further object of the invention is to provide means including the reactors above indicated for controlling the different signals in accordance with track conditions.

While in the following specification I will describe a particular means for controlling the grid circuits of different discharge devices of the system, it will be understood that I am not to be limited thereto, and that any suitable means may be employed to control the different discharge devices in dependence upon the presence of a vehicle in the respective blocks.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawings in which Figs. 1, 2, 4 and 5 represent different embodiments of my invention, and Figs. 3 and 6 represent modifications thereof.

Referring to Fig. 1 of the drawings I have represented at 1 the tracks of a railway system. This track is divided into blocks A, B, C etc. in accordance with common practice, the rails of the different blocks being electrically insulated from each other as indicated at the points 2, 3, 4, etc. At 5, 6 and 7 I have indicated the signaling equipments which are associated with each of the blocks A, B, and C respectively. These equipments are all identical in circuit arrangement, and it will be understood that a similar equipment is associated with each of the different blocks of the railway system.

While any suitable system of signals may be

employed in the equipments 5, 6, 7 I have shown a plurality of lamps which upon illumination indicate the different track conditions as, for example, when the lamp R is energized, the occupied condition of the block A or "danger" is indicated. When the lamp Y is energized the occupied condition of the adjacent block B in the direction of traffic or "caution" is indicated, and when the lamp G is energized the "clear" or 10 "safe" condition of both of the above mentioned blocks is indicated.

I have indicated at 8 a power supply circuit which is normally energized from a source 9 and which may extend throughout the railway system. Energy from the power supply circuit 8 is supplied through transformers 10, 10', 10'' to the exit end of each of the blocks A, B, C respectively, a suitable resistance being included in the circuit for adjusting the magnitude of the electro-motive force supplied to each of the different blocks as desired. At the entrance end of each of the blocks this energy from the track circuit is supplied through transformers 11, 11', 11'' to the grid circuit of electron discharge devices 12, 25 12', 12''. It will thus be apparent that the grid circuit of each of the discharge devices associated with the different blocks is normally supplied with alternating current from the track rails, but that upon the entrance of a vehicle, such as a 30 locomotive, in any of the blocks, the two rails become short circuited through the wheels and axles of the vehicle and the alternating electro-motive force is removed from the grid circuit of the corresponding electron discharge device. 35 These discharge devices are connected in a manner presently to be described to control the signal devices R, Y, G; R', Y', G'; R'', Y'', G'' in each of the respective blocks. Thus, for example, when alternating current is removed from the 40 grid of any of the discharge devices the danger signal in the respective block, and certain of the other signals will become actuated as will presently be indicated.

It will be noticed that the grid circuit of each 45 of the discharge devices is thus one which is inherently protected against faults, such as may occur due to a broken rail, short circuit of the power supply or any other fault which may interrupt the supply of alternating current to the 50 grid of the respective discharge device. Any such interruption has the same effect upon the system as that produced by the presence of a vehicle in the respective blocks, that is, to cause a danger indication to be given.

55 The anode circuit of each of the discharge devices is energized from the power supply circuit 8 and includes a plurality of saturated core reactors which I have indicated in the drawings at 13—19 in the equipment 5, 13'—19' in the equipment 6, and 13''—19'' in the equipment 7. These reactors may be of any suitable construction, but each comprises a direct current winding and an alternating current winding arranged upon an iron, or ferro-magnetic core such that when the 60 direct current winding is energized the iron core becomes saturated and the alternating current winding becomes of low impedance, whereas when the direct current winding is unenergized the alternating current winding is of high impedance. In the drawings I have indicated a 65 bar adjacent the direct current winding of each reactor for the purpose of rendering this winding distinctive. The signals R, Y, G in the different blocks are energized in parallel circuits 70 connected across the power supply conductors 8,

each of these circuits including limiting reactors for purposes later to be indicated. Energization of each of the signals thus connected is controlled by the alternating current windings of the different reactors in accordance with track 5 conditions.

The discharge devices 12, 12', 12'' etc. may be of any suitable construction, but preferably these devices are of the vapor electric type having an anode, a cathode and a grid enclosed in an envelope provided with a conducting gas such as mercury vapor. These discharge devices have the characteristic that their impedance is changed from a very high value to one which is comparatively low in response to a very small 15 change in grid voltage; that is, as the alternating current grid voltage is gradually increased in a positive direction the anode circuit suddenly changes from a very high impedance to a very low impedance, in which condition the discharge 20 device has the capacity to carry a very large current. When the alternating current grid voltage is reduced the impedance changes from the previous low value to a very high or infinite value at substantially the same voltage; that is, 25 the grid voltage at which the change in impedance from a high value to a low value occurs is substantially that at which it changes from a low value to a high value. This character of the discharge device, as indicated, renders it particularly well adapted for the purpose to be herein described since, particularly in wet weather conditions, the voltage variations in response to which the signals are operated are very narrow.

A further understanding of the invention as 30 illustrated in Fig. 1 may now best be had by reference to its operation. Normally direct current 35 flows in the anode circuit of each of the discharge devices, and the different reactors are saturated and their secondary windings are of 40 very low impedance. Considering, for example, the equipment 6 it will be noticed that the alternating current winding of reactor 19' is connected directly in shunt with the lamp R', such 45 that this lamp is normally short circuited and de-energized. In the same way the lamp Y' is short circuited by the alternating current windings of the reactor 16 in equipment 5, and that of reactor 13'' in equipment 7. Similarly the lamp G' is short circuited by the alternating current winding of reactor 15 in the equipment 5. Thus the 50 signal lamps in each of the different blocks are normally deenergized and unlighted.

Let us assume now that a vehicle enters block A traveling in the direction of the arrow, which 55 I have shown therein for the purpose of indicating the direction of traffic. Alternating current is removed from the grid of discharge device 12, thereby causing the direct current windings of each of the reactors 13 to 19 to be deenergized. 60 The alternating current winding of reactor 19' then becomes of high impedance thereby causing the lamp R to be lighted, this lamp being connected directly across the power circuit in series with limiting reactor 20. The lamp R thus indicates the occupied condition of block A. De-energization of the direct current winding of reactor 16 causes its secondary winding to become of high impedance, but this has no effect upon the lamp Y' of equipment 6, which is connected 65 in shunt therewith, for the reason that this lamp is still short circuited by the alternating current winding of reactor 13''. The alternating current winding of reactor 15 now becomes of high impedance thereby causing the lamp G' in equip- 70 75

ment 6 to become lighted, this lamp being energized in a circuit which extends from one side of the circuit 8 through limiting reactor 22', lamp G', alternating current winding of reactor 14' which is now of low impedance and alternating current winding of reactor 18'' which is also of low impedance to the opposite side of the circuit 8. The lamp R indicates the occupied condition of the block A, and the lamp G' indicates the unoccupied or "clear" condition of the blocks B and C.

Now let us assume that the vehicle passes from block A to block B. Alternating current is again supplied to the discharge device 12 and is removed from the grid of discharge device 12'. Lamp R is again short circuited by the alternating current winding of reactor 19. The short-circuit about lamp R' is removed by reactor 19' and this lamp becomes energized. The lamp G'' will be lighted in the circuit extending through limiting reactor 22'' alternating current winding of reactor 14'' and thence to the next block through elements corresponding to those of the circuit previously traced in connection with lamp G'. It will be noticed that the lamp Y in block A will not be lighted since it is short circuited by the reactor corresponding to reactor 16 of the equipment in the block to the right of block A.

If we assume that there is a vehicle in blocks A and C and none in block B, the lamp Y' will be lighted through a circuit extending from one side of the power source through limiting reactor 21', lamp Y', and alternating current winding of reactor 17' to the other side of the power source. The lamp G' will not be lighted since its circuit includes the high impedance of the alternating current winding of reactor 18''. The lamps R' and R will both be lighted.

It will thus be seen that in this system the caution signal Y is not lighted in the block to the rear of a vehicle proceeding along the track unless the second block in the rear is occupied by a vehicle. The danger signal is always given when any block becomes occupied. The "clear" signal is given in response to the approach of the vehicle in the adjacent block.

Referring to Fig. 2 of the drawings I have shown a considerably simplified system by means of which the above results may be accomplished, and which employs a considerably reduced number of line conductors extending between each of the adjacent blocks. The track or grid circuits of each of the discharge devices in this figure and in the remaining figures are similar to those indicated in Fig. 1.

The anode circuits of the discharge devices may be understood by tracing the anode circuit of the device 12' associated with block B, since this circuit is completely illustrated in the drawings. It will be seen that this circuit is divided into three branches, one of which extends from the anode of the discharge device 12' through direct current windings of reactors 23 and 24 in the equipment 5 to the upper conductor of the power supply circuit 8, and thence back to the cathode of device 12'. The second branch extends through the direct current windings of reactors 25', 26' of the equipment 6 to the upper conductor of the circuit 8. A third branch extends through the direct current winding of reactor 27'' in the equipment 7. The anode circuits of each of the other discharge devices are identical with the circuit traced.

Thus, if we assume that the block B is occupied by a vehicle, the above branch circuits are de-

energized. The deenergization of reactor 24 will cause the lamp Y to be lighted since the direct current winding of reactor 26 is energized and, hence, its alternating current winding is of low impedance. The alternating current winding of reactor 23 becomes of high impedance but has no effect upon the signal G since this signal is short circuited by the alternating current winding of reactor 27. Deenergization of reactor 25' causes the lamp R' to be lighted indicating the occupied condition of the block B. Deenergization of reactor 26' has no effect upon signals Y', G', since these signals are both short circuited by reactors 24' and 27'. Deenergization of reactor 27'' causes the light G'' to be lighted, since reactors 23'' and 26'' are both supplied with direct current, and their alternating current windings are of low impedance.

Thus with a vehicle in block B, the lamp G'' in block C is lighted, lamp R' in block B is lighted, and the lamp Y in block A is lighted. If adjacent blocks are occupied the danger signal R in each block will of course become energized.

Thus in this system the caution signal in the block immediately at the rear of a vehicle moving along the track always becomes energized independently of a following vehicle in the second block to the rear. To make the lighting of this signal dependent upon the presence of a following vehicle a slight modification, indicated in Fig. 3 may be made. In accordance with this modification of the system not only the direct current from the advance block is caused to pass through reactor 24' but also that which flows from the rear block also passes through this reactor. Thus the reactor 24', and similarly reactors 24 and 24'', is connected in series both with reactors 23' and 27', which are included in the conductors extending to the opposite adjacent blocks. Thus the alternating current winding of reactor 24' will comprise a substantial short circuit to the lamp Y', except when direct current is removed therefrom by deenergization of both of discharge devices 12 and 12'', as when both blocks A and C are occupied and block B is unoccupied.

In Fig. 4 I have shown a further embodiment of my invention in which the signals are controlled by means employing a single line conductor extending between the adjacent blocks. The control of signals in advance of a vehicle in any block is effected by increasing the magnitude of direct current flowing in the line circuit extending to the advance block. The control of signals of the block at the rear of a vehicle is effected by diminishing the current in the line conductor extending to that block.

The anode circuits of each of the discharge devices may be understood by tracing the circuit of the device 12'. This circuit extends from the upper conductor of the circuit 8 to the cathode and anode of discharge device 12', secondary winding of transformer 29', direct current winding of reactors 30', 25', 26' and 28', in the equipment 6, secondary winding of transformer T in block 5 and direct current windings of reactors 23 and 24 of the equipment 5 to the upper conductor of circuit 8. This circuit is energized by transformer 29' and transformer T connected in series aiding relation for a purpose later to be indicated. It will be seen that the reactors 30', 30'', which are connected in the anode circuits of the respective discharge devices 12, 12', 12'' each constitute a normal short circuit to the secondary winding of the respective transformer 75

T, T', T'' such that the principal electromotive force on the anodes of the different discharge devices is that supplied thereto by the respective transformers 29, 29', 29''. However, when the reactor 30' becomes deenergized the anode potential on the discharge device 12'' is increased by adding to that of the secondary winding of transformer 29'' the potential on the secondary winding of the transformer T', thereby increasing the direct current flowing in the anode circuit of device 12''.

Thus, for example, let us assume that a vehicle occupies the block B, and that the blocks A and C are unoccupied. The above traced circuit is deenergized and the short circuit removed from the transformer T'. The potential upon discharge device 12'' will then be increased and the direct current flowing in the circuit thereof will be increased by a certain amount. The reactors 28, 28' and 28'' in this system saturate at a higher current than the remaining reactors of the circuit and normally their alternating current windings are of high impedance notwithstanding the normal flow of direct current in the direct current windings thereof. When the increased current in reactor 28'' occurs, due to block B being occupied, however, reactor 28'' becomes fully saturated and since reactors 23'' and 26'' are simultaneously saturated the lamp G'' will be caused to light. The deenergization of the anode circuit of discharge device 12' causes the short circuit to be removed from lamp R' and this lamp is accordingly lighted. Similarly deenergization of this circuit causes a short circuit about lamp Y in block A to be removed, and since reactor 26 is now of low impedance the lamp Y lights. Thus in this system, as shown, the caution signal is energized in the block to the right of an occupied block independently of the presence of a following vehicle in the next adjacent block. It will, of course, be apparent that if the adjacent blocks are occupied the danger signals in both blocks will be lighted.

In Fig. 5 I have shown further means whereby the desired signals may be effected by the use of a single line conductor extending between the blocks. In this figure the forward actuation is produced by supplying alternating current over the line extending to the forward block and the rearward actuation is produced by the control of direct current flowing to the rear block. In this system it will be noticed that the danger signals R, R', R'' are connected as before directly across the power supply conductors, whereas the caution and clear signals are energized in a circuit which extends through the conductor leading to the rear block and the transformer t, t', t'' in the rear block. Thus, for example, the circuit of the lamp G' extends from the upper conductor of the power circuit 8 through the alternating current windings of reactors 26', 23', signal G', condensers 31', 32, limiting reactor 33, secondary winding of transformer t back to the upper conductor of the power supply. The secondary windings of the transformers t, t', t'' however, are subject to control of the discharge device in the corresponding block through reactors 34, 34', 34'' respectively. The direct current windings of the reactors 34, 34', 34'', however, are normally energized and hence their alternating current windings normally constitute very low impedances connected in shunt relation with the secondary winding of the associated transformers t, t', t'' through the limiting reactor. This shunt so reduces the secondary voltage as to

cause the clear signal in the advance block to be extinguished. The limiting reactors 33, 33', 33'' are such that the potential across the windings of the reactors 34, 34', 34'' is normally sufficiently reduced to prevent sufficient energization of the clear signal controlled thereby to cause it to light, but at the same time is sufficient to maintain the impedance of the secondary circuit of the respective transformers t, t', t'' sufficiently high to prevent excessive current when the reactors 34, 34', 34'' are saturated.

Let us assume that the block B is occupied. The anode circuit of the device 12' is then deenergized causing the lamp R' to be lighted. The low impedance shunt to transformer t' is removed and alternating current is then supplied to the lamp G'' causing it to light. Reactors 23 and 24 are desaturated preventing energization of the lamp G in the rear block and causing the lamp Y in the rear block to be lighted dependently upon the presence of a vehicle in the block to the right of block A. Thus in this figure the caution signal in the block immediately at the rear of a vehicle becomes energized dependently upon the presence of a following vehicle in the second block at the rear.

The purpose of reactor 39 and condensers 31 and 32 in the equipment 5 and the corresponding elements in equipments 6 and 7 is to render the alternating and direct current circuits which are superposed upon the single line conductors independent of each other.

In signal systems as practically employed it may occur that the phase relation between the power supply in the different blocks may vary. Thus, for example, the signal circuits in a certain block may be supplied from a separate distribution system from that of an adjacent block and a considerable difference in phase may exist between the two systems. Accordingly, it may occur that alternating current is applied to the grid of a discharge device of the system from the power supply circuit of one block and to the anode circuit of said discharge device from the power supply system of another block. Thus the alternating current which is supplied to the anode circuit may not be in proper phase relation with the grid voltage to produce proper operation of the discharge device. When this condition is encountered, the desired operation may be had by rectifying the potential which is applied to the grid as shown in Fig. 6. In this figure potential which is supplied to the grid of the discharge device from the track through transformer 11 is rectified by means of a rectifier 35 of any suitable type such, for example, as those comprising a copper plate having cuprous oxide formed thereon and mounted between suitable electrodes, as disclosed in Patents No. 1,640,335 to Lars O. Grondahl, issued August 23, 1927. This rectifier, it will be seen, is connected directly in series with the transformer 11 and smoothing condenser 36. This condenser is connected directly between the cathode and grid of the discharge device 12. The rectifier 35 is of course unilaterally conducting causing the condenser to charge during the positive half cycles whereupon the charge is maintained by the condenser through the alternate half cycle.

It may also occur in the operation of systems of the type disclosed that the discharge in the vapor electric devices may fail to cease upon the removal of alternating electromotive force from the grid, this may, for example, be due to the presence of foreign gases within the envelope,

high gas pressure, or electron emission, under certain conditions, from the grid. To protect against an occurrence of this nature, I have provided means which I have shown in connection with Fig. 4 for purposes of illustration. It will be apparent however that these protective means, now to be described, are equally applicable to each of the different systems described.

Associated with each of the electron discharge devices in Fig. 4 is a protective discharge device indicated at 12_p , $12_{p'}$ and $12_{p''}$. Grid potential for the operation of these protective devices is supplied from the track through an additional secondary winding on the associated grid transformer 11 , $11'$, $11''$. The winding of the transformers 11 , $11'$, $11''$ which is connected to the grid of the protective discharge device is also connected in series with the secondary winding of an additional transformer 31 , $31'$, $31''$. The primaries of these latter transformers are connected directly across the power circuit. Thus, included in the grid circuit of the discharge devices are two sources of potential comprising the two secondary windings. These windings are so connected that their potentials are in opposed phase relation, such that normally the potential upon the grid of the discharge device is such that no current flows in the anode circuit of the discharge device. Thus, the protective discharge devices 12_p , $12_{p'}$, $12_{p''}$ are normally inactive, while the discharge devices 12 , $12'$, $12''$ are normally active. The anode circuit of each of these protective discharge devices includes a resistance 38 , $38'$, $38''$ which resistance is also in circuit with the primary winding of transformers 29 , $29'$, $29''$, which normally supply excitation to the anode circuits of the respective discharge devices 12 , $12'$, $12''$.

If we assume, for example, that the block B becomes occupied by a vehicle, alternating electromotive force is removed from the grid of device $12'$ and that supplied to the grid of device $12_{p'}$ is increased in proper phase to reduce the impedance of the tube, since there is now no potential across the secondary winding of $11'$ to oppose that of transformer $31'$. A large current is then caused to flow in the anode circuit of device $12_{p'}$ and thence through resistance $38'$. The potential in the resistance $38'$ occurs during the same half cycle in which the anode of discharge device $12'$ is positive and, accordingly, so reduces the electromotive force supplied to the primary winding of transformer $29'$ that the anode circuit of discharge device $12'$ is insufficiently energized to cause the device to operate. Thus the device 12 will become inactive due to operation of the device $12_{p'}$.

While I have shown particular embodiments of my invention, it will of course be understood that I do not wish to be limited thereto, since many modifications may be made, both in the circuit arrangement and in the instrumentalities employed, and I contemplate by the appended claims to cover any such modifications as fall within the true spirit and scope of my invention.

What I claim as new and desire to secure by Letters Patent of the United States, is:

1. In a railway block signal system, a single electron discharge device in each block, means for controlling each of said discharge devices in accordance with track conditions in the respective block, means in each block for producing a plurality of indications, and means controlled entirely by said single discharge devices for causing said indicating means to produce indications in

accordance with track conditions in the different blocks.

2. In a railway block signal system, a single electron discharge device in each block, means for controlling each of said discharge devices in accordance with track conditions in the respective block, means in each block for producing a plurality of indications, and means entirely electrical responsive solely to the anode current in said discharge devices for causing said indicating means to produce indications in accordance with track conditions in the different blocks.

3. In a railway block signal system, a single electron discharge device in each block, means for controlling each of said discharge devices in accordance with track conditions in the respective block, indicating means in each block, and means controlled solely by said discharge devices for causing said indicating means in each block to indicate track conditions in the respective block and in an adjacent block.

4. In a railway block signal system, a single electron discharge device in each block, means for controlling each of said discharge devices in accordance with the occupied condition of the respective block, indicating means in each block, and means controlled solely by said discharge devices for causing said indicating means in any block occupied by a vehicle to give a certain indication and the indicating means in an adjacent block to give a different indication.

5. In a railway block signal system, an electron discharge device in each block, means for controlling each of said discharge devices in accordance with the occupied conditions of the respective block, indicating means in each block, and means controlled by said discharge devices for causing said indicating means in any block occupied by a vehicle to give a certain indication, the indicating means in one of the adjacent blocks to give a different indication, and the indicating means in the opposite adjacent block to give a third indication.

6. In combination, a source of electromotive force, a circuit including said source and a plurality of electro-responsive devices, each of said electro-responsive devices being connected in a separate branch of said circuit, inductive means in each branch of said circuit, and means for controlling the inductance of said inductive means to cause selective response of said devices.

7. The combination, in a railway block signal system, a signal device in each block, a source of electromotive force, a circuit including said source and said signal device, an inductance device connected to control the energization of said signal device, and electron discharge means in each block for controlling the inductance of said inductance device in accordance with track conditions in one of said blocks.

8. The combination, in a railway block signal system, of a saturable reactor in each block, a plurality of signals in each block, and means including said saturable reactor for selectively controlling the signals in each block in response to the track conditions in the respective block and in an adjacent block said means including means for controlling the signals in response to the impedance of said reactor.

9. The combination, in a railway block signal system, of a plurality of signals in each block, a plurality of inductive reactors in each block so connected and arranged in circuit with said signals that each signal is operative independently upon the inductance of at least one associated

reactor, and means responsive to the condition of the different blocks for selectively controlling the inductance of said reactors to cause operation of certain of said signals determined in accordance with the block or blocks, occupied.

10. The combination, in a railway block signal system, of a plurality of signals in each block, a plurality of inductive reactors in each block so connected and arranged in circuit with said signals that each signal is operative dependently upon the inductance of at least one associated reactor, and means including an electron discharge device in each block, each of said discharge devices being responsive to the occupied condition of the respective block, for selectively controlling the inductance of said reactors to cause operation of certain of said signals determined in accordance with the block or blocks occupied.

15. 11. The combination, in a railway block signal system, of a plurality of signals in each block, a plurality of reactors in each block, each of said reactors having a winding the impedance of which is dependent upon the degree of saturation of the reactor, said windings being so connected and arranged in circuit with said signals that each signal is operable dependently upon the degree of saturation of one or more associated reactors, and means in each block for controlling the degree of saturation of certain of said reactors in accordance with the occupied condition of the respective block.

12. The combination, in a railway block signal system, of a plurality of signals in each block, a plurality of reactors in each block, each of said reactors having a winding the impedance of which is dependent upon the degree of saturation of the reactor, said windings being so connected and arranged in circuit with said signals that each signal is operable dependently upon the degree of saturation of at least one associated reactor, and means in each block for controlling the degree of saturation of certain of said reactors in the respective block and in an adjacent block in accordance with the occupied condition of the respective block thereby to cause a different display of said signals in said blocks for different conditions of occupancy of said blocks.

13. In a railway block signal system comprising a plurality of blocks, a signal associated with each block, and electrical means all of whose component parts are stationary with respect to each other, said electrical means being responsive to the presence of a vehicle in any block for operating the signal in the block in advance of the vehicle dependently upon the clear condition of the block in advance of the vehicle.

14. In a railway block signal system, a plurality of signals in each block, a line conductor extending between a pair of adjacent blocks, and means for controlling a signal in each block of said pair of adjacent blocks over said conductor from the other block of said pair.

15. The combination, in a railway block signal system, of a vapor electric device in each block, means for supplying an electromotive force to each of said vapor electric devices varying in accordance with the occupied condition of the respective block, said vapor electric device being adapted to break down and pass current only when said electromotive force varies beyond a predetermined value, a plurality of signal devices, and means entirely electrical for selectively

controlling said signal devices in response to operation of said vapor electric devices.

16. The combination, in a railway block signal system, of a vapor electric device in each block, each of said vapor electric devices having an anode circuit, means for controlling each of said vapor electric devices in accordance with the occupied condition of the respective blocks, inductive reactance means, means connected in the anode circuit of each of said devices to control the inductance of said reactance means, a plurality of signals in each block, and means including said reactance means for selectively controlling said signals.

17. The combination, in a block signal system, of a plurality of signals in each block, a pair of line conductors extending between each pair of adjacent blocks, and means for transmitting direct current from any block to an adjacent block over said pair of line conductors extending to said adjacent block and for transmitting alternating current to the opposite adjacent block over said pair of line conductors extending to said opposite adjacent block, and means for operating predetermined signals in said adjacent blocks in response to said currents.

18. The combination, in a block signal system, of a plurality of signals in each block, a pair of line conductors extending between each pair of adjacent blocks of said system, and means in one block of each pair for sending direct current over said line conductors to the opposite block of said pair and means in the opposite block for sending alternating current over said line conductors to said one block of the pair and means in each block for selectively controlling predetermined signals in response to said currents.

19. In a railway block signal system, a plurality of signals in each block, a line conductor extending between a pair of adjacent blocks, and means for controlling a signal in each of said pair of adjacent blocks over said conductor from the other block of said pair, said means including means for transmitting current in opposite directions over said conductor having different relative intensities thereby selectively to control said signals.

20. The combination, in a railway block signal system comprising a plurality of blocks, of clear, danger, and caution signals in each block, a plurality of reactors in each block, said reactors being connected and arranged selectively to control said signals, and means operable dependently upon the condition of said blocks selectively to control the inductance of said reactors to cause said danger signal to be actuated in any block occupied by a vehicle, said caution signal to be actuated in an unoccupied block adjacent to and on the rearward side of a block occupied by a vehicle, and said clear signal to be actuated in an unoccupied block when the block in advance thereof is unoccupied.

21. The combination, in a railway block signal system comprising a plurality of blocks, of clear, danger, and caution signals in each block, a plurality of reactors in each block, said reactors being connected and arranged selectively to control said signals, and means operable dependently upon the condition of said blocks selectively to control the inductance of said reactors thereby to cause said danger signal to be actuated in any block occupied by a vehicle, said caution signal to be actuated dependent upon the occupied condition of both of the two opposite adjacent blocks, and said clear signal to be energized dependent

upon the unoccupied condition of one of said adjacent blocks and the occupied condition of the other adjacent block.

22. The combination, in a block signal system of a source of electromotive force in each block, a circuit in each block including said source and a plurality of signal devices, each of said signal devices being connected in a separate branch of said circuit, inductive means connected in each branch of said circuit, and means responsive to the condition of said blocks selectively to control the inductance of said inductive means to cause different signals to be actuated in any block in accordance with the different condition of occupancy of the respective block and an adjacent block.

23. The combination, in a railway block signal system, of a plurality of reactors in each block, each of said reactors having a winding the impedance of which is dependent upon the degree of saturation of the reactor, said windings being so connected selectively to control said signals that each signal is operable independently upon the degree of saturation of at least one associated reactor, and means all of whose parts are stationary with respect to each other during operation selectively to control the saturation of said reactors in accordance with the track conditions in the different blocks thereby to cause different signals to be operated in accordance with different track conditions.

24. The combination, in a railway block signal system comprising a plurality of blocks, of a plurality of signals in each block, and means all of whose component parts are relatively stationary for selectively controlling said signals in accordance with the different conditions of occupancy of adjacent blocks, said means comprising a plurality of saturable reactors in each block, means in each block selectively to control the saturation of certain of said reactors in response to track conditions in the different blocks, said reactors being so connected and arranged in circuit with said signals that different signals are actuated in accordance with the different conditions of occupancy of said blocks.

25. The combination, in a railway block signal

system, of a plurality of signal devices in each block, a plurality of reactors in each block, each of said reactors having a winding, means all of whose component parts are stationary with respect to each other for controlling the saturation of said reactors in accordance with track conditions in the different blocks, said windings being so connected selectively to control said signal devices that as a vehicle traverses said blocks a certain signal device is actuated in any block occupied by said vehicle and either of two other signal devices is actuated in any block when unoccupied and immediately in advance of the vehicle, the signal device actuated being dependent upon whether a second block in advance of the vehicle is occupied or unoccupied.

26. The combination, in a block signal system, of means in each block for producing a plurality of signal indications, means in each block for controlling said last means to cause different signal indications to be produced dependent upon the condition of occupancy of the respective block and an adjacent block, said means including a saturable reactor, and means to control the saturation of said reactor in response to the condition of the respective block.

27. The combination, in a railway block signal system, of a magnetic device in each block having an iron core and a winding thereon, means to produce a unidirectional flux in said core, and means whereby the flux in the core of the magnetic device in any block may have either of two intensities dependent upon whether an adjacent block is occupied or unoccupied, and signal means connected to respond to changes in impedance of said winding due to changes in intensity of said unidirectional flux.

28. The combination, in a railway block signal system, of a magnetic device in each block having a core and a winding thereon, means to produce unidirectional flux of either of two intensities in said core and to interrupt said flux depending upon different track conditions in the respective block and an adjacent block, and a signal device controlled by the impedance of said winding.
